2 SHEETS SHEET 2.

UNITED STATES PATENT OFFICE.

JOHN H. ABEL, OF MONESSEN, PENNSYLVANIA.

SLAG-REMOVER.

1,303,225.

Specification of Letters Patent. Patented May 13, 1919.

Application filed May 4, 1918. Serial No. 232,530.

To all whom it may concern:

Be it known that I, JOHN H. ABEL, a citizen of the United States, residing at Monessen, in the county of Westmoreland and State 5 of Pennsylvania, have invented certain new and useful Improvements in Slag-Removers, of which the following is a specification.

This invention relates to furnaces, and 10 more especially to the linings thereof; and the object of the same is to produce means within a slag pocket whereby the walls of the same are protected from intense heat and the slag accumulating at the bottom of 15 the pocket may be conveniently removed.

To this end the invention consists in a movable bottom whose side sections may be dropped to a lower level than its intermediate section so that the latter may be with- 20 drawn.

Further details will be found in the following specification and claims, and reference is made to the drawings, wherein:

Figure 1 is a front elevation of two 25 pockets, the bottom at the left therein being raised and at the right in this view being lowered.

Fig. 2 is a vertical section through the pocket at the left of Fig. 1 and

30 Fig. 3 a similar section through the pocket at the right of Fig. 1.

Fig. 4 is a sectional detail on the line 4—4 of Fig. 2.

The furnaces may be of any appropriate 35 size and configuration, but as illustrated their slag pockets 1 and 2 are formed with walls of masonry or brick work, arched at the top, provided with rear bridge walls 3 about as shown, and having their bottoms 40 made up as described hereinafter. The numerals 4, 5, and 6 designate pillars which may also be of masonry as indicated, and their disposition about that shown in the drawings. In the bridge wall 3 at its trans- 45 verse center is left a recess indicated at 7. The side walls of each pocket are undercut to flare downward as shown, and to these walls may be attached facing plates 8 of metal, possibly protected by a coating 9 of loam. In fact, these plates may extend 50 around the rear end of the pocket as seen at 8' but we are concerned principally with the side walls. The latter therefore di- 55 verge downward so that the lower portion of the pocket is wider than the upper part.

The bottom of each pocket is constructed as follows: The pillars 4 carry a pillar block 10 in which moves a fulcrum bar 11 which supports the inner ends of four I-beams 12 spaced about as best seen in Fig. 1 and 60 held in such spaced relation by braces not necessary to show. These beams carry overlying plates 13 and 14 which extend the full length of the pocket and close the bottom thereof excepting where they are spaced between their inner edges. The forward ends of the I-beams overlie a cross bar 15 adapted when raised by power attached to chains 16 (which power mechanism need not be shown) to lift said forward ends of the 70 beams so that their bodies will stand practically horizontal as seen in Fig. 2. At other times the cross bar may rest on the forward pillars 6 as shown in Fig. 3 and at this time the beams and their plates will be inclined 75 slightly forward. Erected upon said plates are side walls 17 which are preferably made of brick, the outer faces of these walls being inclined upward and inward as indicated at 80 18 and their upper ends having tongues 19; 80 and the inner ends of these walls are connected by a cross wall 17' standing normally just forward of the bridge wall 3. The plates 13 and 14 are also paved with old brick as at 20. It will not be necessary to 85 illustrate the fact, but over this paving and against the inner faces of the walls may be applied a coating of sand in case the heat within the furnace is expected to be excessive. So much of the bottom as has thus 90 far been described relates to the parts at the opposite sides thereof, which are side sections preferably complementary to each other, and they are mounted on a common pivot 10 and raised and lowered at their 95 outer ends by a common cross bar 15.

Between the sections of the bottom de- 100 scribed above is disposed another I-beam 22 whose inner end is hooked or bent upward at right angles as at 21 and adapted to enter the recess 7 in the bridge wall. A plate 23 is secured upon this I-beam and closes the space between the plates 13 and 14 as seen in Fig. 1. The forward end of this I-beam 22 may rest on the cross bar 15 when the lat- 105 ter is raised as seen in Fig. 2, but when this cross bar is lowered the intermediate I-beam is sustained by a series of rollers 25 mounted in bearings 26 carried by supporting beams 28, which in turn are supported by pillars 4 110

and 5 in such position that they constitute, with their rollers, an inclined trackway. 29 indicates a chain attached to the I-beam 22 and leading to any suitable source of power by 5 which to withdraw this beam and its plate 23 and the hook 21 from position.

The parts being assembled and the brick work erected and the floor built in as shown in Fig. 1 (with or without the sand or other protective coating), the furnace is charged and the fire lighted. The intense heat generated therein would warp and otherwise destroy the facing plates 8 if it were not for their protective coating of loam 9 and particularly the protective walls 17. Eventually the pocket becomes to an extent filled with slag which it is desirable to remove. With the parts standing at normal, as seen at the left of Fig. 1 and in Fig. 2, the cross bar 15 is first lowered so that the parts assume the position shown at the right of Fig. 1 and in Fig. 3. This lets most of the bottom down to an inclined position and tilts the walls 17 and the cross wall 17' forward; but the intermediate I-beam 22 is now supported on the rollers 25 of the track and its plate 23 is automatically held a little higher than the plates 13 and 14 as will be clear. Tension applied to the chain 29, or any pull in the direction of the arrow adjacent it in Fig. 3 will now withdraw the hooked intermediate section whose upturned end or hook 21 is behind the cross wall 17'. The withdrawal of this section of course ruptures said cross wall as the hook moves forward out of the recess 7 and the slag in mass is drawn out of the pocket. Doubtless this will draw with it the side walls 17 and the flooring, but the fixed walls of the furnace and the plates are unimpaired and the bridge wall 3 has been protected by the cross wall 17'. The entire mass of slag with the adhering brick work etc. having been withdrawn, the parts are restored to their former position and new flooring and walls built in. This I find can be done while the furnace is yet in use and therefore the loss hitherto occasioned by permitting the furnace to become cooled is eliminated.

50 The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

65 1. In a slag pocket of the type described, a slag remover comprising a furnace bottom made in three sections, two of which are spaced to admit the third, means for tilting

said three sections toward the front, and means for withdrawing the intermediate section longitudinally when desired.

2. In a slag pocket of the type described, a slag remover comprising a bottom made 70 in three sections, two of which are spaced to admit the third, means for raising and lowering the front ends of said two sections simultaneously, and means for withdrawing the intermediate section when desired.

75 3. In a slag pocket of the type described, a slag remover comprising a furnace bottom made in three sections, two of which are spaced to admit the third, a cross bar underlying the front ends of all said sections for 80 raising and lowering them when desired, and a roller-carrying track underlying the intermediate section and with its rollers standing at a height to support this section when the other sections descend with said 85 cross bar, for the purpose set forth.

4. In a slag pocket, the combination with the walls, and a pillar block at the bottom near the rear of the pocket; of a fulcrum bar pivotally mounted in said block, a pair of beams supported at their inner ends on said fulcrum bar, means for raising and lowering their outer ends, an inclined track having fixed rollers mounted between said beams, and an intermediate beam between 95 the others and adapted to rest on said rollers and to be longitudinally removable thereover, for the purpose set forth.

5. The herein described slag pocket bottom comprising two pair of parallel spaced beams, plates secured upon the members of the pairs and spaced from each other at their inner edges, a pivotal support for the inner ends of these beams, means for raising and lowering their outer ends simultaneously; an intermediate beam overlying said pivotal support and raising means and upturned at its inner end, a plate secured upon this beam and filling the space between said other plates, supports for the intermediate beam for sustaining it at a higher level than the lowest level to which the other beams are lowered, and walls erected upon the side plates.

100 6. The herein described slag pocket bottom comprising two pair of parallel spaced beams, plates secured upon the members of the pairs and spaced from each other at their inner edges, a pivotal support for the inner ends of these beams, means for raising and lowering their outer ends simultaneously, an intermediate beam overlying said pivotal support and raising means and upturned at its inner end, a plate secured upon this beam and filling the space between said other plates, supports for the intermediate beam for sustaining it at a higher level than the lowest level to which the other beams are lowered, side walls erected upon the side plates, a cross wall connecting the inner ends 115 120 125 130

of said side walls **forward of** said upturned end, and means for withdrawing the intermediate beam longitudinally when the other beams are dropped.

5. 7. In a slag pocket, the combination with fixed side walls flaring downward, and plates secured to the flaring portions thereof; of removable bottom, walls erected thereon and with their outer faces converging upward 10 to fit against said plates when the bottom is in normal position, and means for withdrawing the intermediate portion of said bottom longitudinally.
8. In a slag pocket, the combination with 15 fixed side walls flaring downward, and plates secured to the flaring portions thereof, the rear end of the pocket having a bridge wall

with an upright recess; of a vertically movable bottom in three sections, walls erected on the side sections thereof with their outer faces converging upward to fit against said plates when these sections are in position, the intermediate section being movable longitudinally between said side sections, and an upstanding hook at the inner end of said intermediate section entering said recess, the whole for use substantially as described. 20 25

In testimony whereof I affix my signature in presence of two witnesses.

JOHN H. ABEL.
